UNITED STATES PATENT OFFICE

IGNAZ SABLÍK, OF STRAMBERG, CZECHOSLOVAKIA

POWDERY MATERIAL FEED APPARATUS

Application filed August 31, 1931, Serial No. 560,459, and in Czechoslovakia April 7, 1931.

This invention relates to an apparatus for feeding powdery material such as cement and the like.

An object of the invention is to provide a compressed air feed plant, in which the material to be fed is discharged, for example by dead weight, into a reservoir until the said container is completely filled. At the upper end of the reservoir is arranged a check member which is closed through the pressure of the material. The closing of the said check member controls a medium such as compressed air or liquid, the rod of the said check member being formed as a controlling piston operating in a cylinder, and the movement of the controlling piston directly or indirectly checks the admission in the reservoir of the material, whereby compressed air is admitted therein, and the material discharged from the container.

Another object of the invention is to provide two reservoirs which are alternately and by turns filled and discharged, the piston of the control cylinder operating a reversible cock which allows compressed air to enter one of the reservoirs and positively checks the passage of the material into such container.

Other objects of the invention will appear from the hereinafter contained description, when considered in connection with the accompanying drawings, illustrating two embodiments of the invention and in which

Fig. 1 is a front elevation of a one-reservoir apparatus,

Fig. 2 is a front elevation, and

Fig. 3 a side elevation of a two-reservoir apparatus.

Fig. 4 shows the check members in a two-reservoir apparatus on an enlarged scale.

Referring to the drawings, 1 is a cylindrically formed reservoir having at its upper end a hopper 2 for the powdery material, to which the material is fed by the piping 3. Intermediate between the reservoir and the hopper is mounted a check member 4. If desired, another check member may be provided at the bottom end of the reservoir and connected to the discharge pipe 5. When the check member 4 is opened, and the reser-

voir 1 completely filled by the material supplied, the check member 6, which is inserted in the cover of the reservoir, is lifted by the pressure exerted by the material, and will form a seal. Through the lifting of such check member, a control slide 7 mounted on the stem of the check member is lifted, which slide is adapted to cause the controlling medium (compressed air or water or the like) to act on the piston of a control cylinder 8 from above, whereupon the piston will travel downward. To the rod 9 of the said piston is, at 10, jointed a double lever having its fulcrum at 12. To the lever is secured a rod 13 carrying the check member 4. The downward stroke of the piston of the control cylinder 8 raises the check member 4 thus cutting off the supply to the reservoir of the material. Through the lifting of the right end of lever 11, a lever 14 is released, said lever being secured, in the manner of a safety valve, to a check member 15 inserted in the compressed air feed pipe 16. The lever 14 is adapted to carry a sliding weight 17, moving in a guide. Displacement of the sliding weight 17 along the guide will alter the torque of the lever 14 and thereby the power which is acting on the rod 18, of check member 15, in a vertical direction. Thereby I obtain that a predetermined working pressure provided in the pipe 16 is required to open the said member, while the pressure against which the member may be closed may be substantially less.

When the check member 15 is opened, compressed air will be delivered through a piping 19 and discharge valve 20, to the top of the reservoir, and through branch 21 and discharge valve 22 to the bottom part of the reservoir. In this manner, pressure is exerted against the powdery material from above, and an auxiliary pressure is simultaneously exerted at the bottom, so that the reservoir will be readily discharged. Since, during such discharge, no further pressure is exerted against the check member 6 by the material to be fed, this member will travel downward, whereby the control slide 7 is reversed, so that the controlling medium is discharged into the exhaust. Thereby the controlling piston within the cylinder 8 will be reversed,

causing thereby the reversal of all the parts of the device so that new material to be fed will enter the reservoir and the working cycle begin again.

In the two-reservoir embodiment shown in Figs. 2 and 3, the control member 23, which corresponds to the control member 6 in Fig. 1, operates alike; a control slide 24 directs a control medium, which is supplied from some source, by means of an annular pipe 23, to the space above the piston of a control cylinder 26, while a member 27, which corresponds to the check member 23 provided within the other reservoir, will direct the controlling medium unto the space below the piston of the control cylinder 26, by means of a control slide 28, when the control slide is in the corresponding position, that is, when a reversal has taken place. On the rod 29 of the piston of the control cylinder 26 is mounted a lever 30 which operates a reversing member 46 such as, for example, a cock inserted in the compressed air pipe 31 and adapted, according to its position, to allow compressed air to enter one of the reservoirs through the upper discharge valves 32, 33 and lower discharge valves 34, 35. At the lower ends of the reservoir are provided check members 36, 37 which may be formed as slides, and operate rods 38, 39 secured to the lever 30. To the lever 30 are also secured rods 40, 41, operating the check members 42, 43, which allow the material to be fed to enter the reservoir from the feed pipes 44, 45. Within the compressed air pipe 31 is inserted a check member 47 corresponding, structurally, to the member 15 of the one-reservoir embodiment and serving, in the two-reservoir embodiment, as an air economizer, not permitting access to the plant, of the compressed air, until the working pressure is attained through the subsequent operation of an air condenser required for keeping the plant running. By such temporary cutting off, I prevent excessive discharge into the dust-removing pipe of compressed air.

In Fig. 4 showing the separate parts of the control member 23 on an enlarged scale, 48 is a valve cone, 49 the stem thereof, 50 is a control slide controlled from above by the spiral spring 51. If the valve cone is in its open position, the intake pipe 52 of the controlling medium is connected with the feed pipe 53 leading to the top of the control cylinder 26, while the exhaust, that is, discharge pipe 54 is closed. If the valve cone 48 is lifted, communication between the pipes 52 and 53 is cut off and an annular duct 55 is lifted, and raised, until it will allow the controlling medium to move from the pipe 53 into pipe 54. A washer 57 is provided to prevent any corrosive action of the powdery material on the guide of the stem of bushing 56. A pipe 58 which is connected to the dust remover 65 allows excessive air to be discharged.

While the invention has been illustrated in what is considered its best application, it may have other embodiments without departing from its spirit and is not, therefore, limited to the structures shown in the drawings. 76

What I claim is:

1. In a powdery material feed apparatus operated by compressed air, a cylindrically formed reservoir, a check member mounted at the upper end thereof, and which is closed by the pressure of the material, said check member controlling a controlling medium, a hopper mounted at the upper end of the reservoir, a feed pipe communicating with said hopper, 80 a control cylinder, a piston traveling therein, a control slide operated by said check member for controlling said piston, a piston rod, a double lever secured thereto, another lever, another check member, on which the second mentioned lever is mounted, a compressed air feed pipe, in which the said check member is inserted, a sliding weight inserted in the last mentioned lever, a guide in which moves the sliding weight, a stem to which the check member is secured, a pipe supplying compressed air to the top of the reservoir and another discharge valve controlling this supply. 85

2. In a powdery material feed apparatus, a combination with two reservoirs, each having intake and discharge openings at the top and bottom, a controlling valve cone in each reservoir and a control slide operated by each valve cone, said valve cones supplying controlling medium to the top and bottom respectively of the control cylinder, an annular pipe in each reservoir, a control cylinder exterior of the said reservoirs, a piston traveling in said cylinder, the said annular pipe supplying controlling medium to the space above said piston, a piston rod, a lever secured to said piston rod, a reversing member operated by said lever, a compressed controlling medium pipe in which the reversing member is inserted, an upper and a lower discharge valve in each reservoir, another check member at the bottom of each reservoir positively operated by the intake and discharge of the compressed medium, two rods operating, respectively, one of the said other check members, two other rods equally secured to the said lever, closing members each of which is acted upon by one of the said other rods, a feed pipe communicating with each reservoir, and a closing member exterior of the reservoirs and inserted in the said compressed medium pipe, the said closing member acting as an air economizer, closing itself when a predetermined pressure is exerted, while it opens when a higher pressure is exerted against it. 105

In testimony whereof I have signed my name to this specification.

IGNAZ SABLICK.
